UNITED STATES PATENT OFFICE.

GODFREY ENGEL, OF BALTIMORE, MARYLAND.

FLOW-REGULATING DEVICE FOR SOLID MATERIAL.

SPECIFICATION forming part of Letters Patent No. 733,175, dated July 7, 1903.

Application filed November 18, 1902. Serial No. 131,871. (No model.)

To all whom it may concern:

Be it known that I, GODFREY ENGEL, a citizen of the United States, and a resident of Baltimore, Maryland, have invented certain 5 Improvements in Flow-Regulating Devices for Solid Material, of which the following is a specification.

My invention relates to certain improvements in mechanism for controlling the flow 10 of granular or fibrous solids, and has to do more particularly in the case of the mechanism illustrated with a device for regulating the discharge of sugar from a cooler.

The main object of the invention is to provide 15 mechanism which shall be operated by changes in the level of solid, granular, or fibrous material to open or close a conduit for supplying material to or conducting it from the body of the same under treatment.

20 A further object of the invention as applied to the mechanism illustrated is to provide means for so controlling the flow of sugar or like substance from a cooler that said cooler is always kept filled to a predetermined 25 level, the mechanism being designed to close the outlet from the cooler whenever the level of the sugar has fallen below a predetermined point and to open said outlet as soon as the level of the sugar has risen again to the desired point.

These objects I attain as hereinafter set forth, reference being had to the accompanying drawings, in which—

Figure 1 is a sectional elevation of a sugar-cooler, showing my improved feed-regulating device as applied thereto. Fig. 2 is an enlarged sectional elevation of the upper portion of the cooler illustrated in Fig. 1, showing the detail construction of a portion of the 35 controlling - valve spindle and its attached parts. Fig. 3 is a sectional elevation of a portion of the lower part of the cooler illustrated in Fig. 1, showing the detail construction of the discharge - valve. Fig. 4 is a sectional 40 plan view on the line 4-4, Fig. 1. Fig. 5 is a side elevation, partly in section, showing the device as viewed from a position ninety degrees from the sectional plane of Fig. 1; and Fig. 6 is an outside plan view of the device.

50 In the accompanying drawings, A represents the casing of a sugar-cooling device, which in the present instance consists of a

cylindrical body having top and bottom conical sections a and a' , the former of these having suitably connected to it a hopper-section 55 a^2 , which is shown as provided with a removable cover-plate and forms the inlet into the casing for material to be cooled. The latter conical section a' is connected to discharge-conduits a^3 . It will be seen that while the 60 portion a is riveted to and forms part of the cylindrical body of the casing the lower part a' is simply suspended under the cylindrical body portion by means of suitable hangers a^4 , attached as shown in Fig. 5. The lower edge 65 of the cylindrical body of the casing is provided with a flanged or upwardly-turned trough-section a^5 , and within said body are fixed two tube-sheets a^6 and a^7 , there being a number of tubes a^8 extending between these and an inlet a^9 and an outlet a^{10} for cooling fluid designed to be circulated between said tube-sheets and around the tubes connecting them. Upon the hopper-section a^2 is placed a cover-plate B, in which is formed a bearing b for a 75 horizontal driving-shaft b' , having upon it a beveled gear b^2 . The plate B is also provided with an overhanging arm b^3 , through which extends a vertical shaft b^4 , this shaft being splined to a second beveled gear-wheel b^7 , 80 meshing with the gear-wheel b^2 and attached to a valve-rod b^5 , this latter being held in position by means of a nut b^6 . It will be understood that the gear-wheel b^2 is provided with a spline fitting a suitable keyway in 85 the shaft b^4 , so that said shaft is free to revolve with the said gear-wheel and also to move vertically through the arm b^3 and the cover-plate B. To the lower end of the said rod b^5 is fixed a valve C, designed to fit a seat 90 in the lowest portion of the conical section a' and when closed to prevent the flow of material from the cooler. This rod extends through a tube c , which, like the other tubes, is extended, so as to be held in the tube-sheets 95 a^6 and a^7 , and in addition is provided with portions which extend both above and below said sheets. To the lower extended portion of this tube is fixed a shield or hood c' , whose side portions extend over the valve C and approach to within a relatively short distance of the bottom of the lower conical section a' .

The lower end of the shaft b^4 is provided

with a screw D, the elements of whose blade or blades are radial and inclined downwardly, there being a tubular hood d fixed just below the said screw and extending downwardly 5 over the upper end of the tube c.

In operation cooling fluid—such as ammonia, brine, &c.—is passed into the opening a⁹ and out of the opening a¹⁰, while sugar or other material to be cooled is introduced into 10 the hopper-section a², thus having its temperature lowered during its passage through the tubes a⁸. It has been found in practice that if the level of the material in the cooler falls below the level of the upper tube-sheet 15 a⁶ the low temperature of said tube-sheets and tubes will cause moisture to condense thereon, with the result that the material operated upon becomes dampened and soon clogs or chokes the device, so as to materially 20 interfere with or prevent the operation of the same. With my device, however, at first the valve C remains closed, and thereby causes the cylindrical portion, as well as the lower conical part of the casing, to be filled with 25 sugar, none of this being allowed to escape until its level has risen sufficiently to cause the screw D to rest upon it. This screw is constantly revolved by means of power applied through shaft b¹, gear-wheels b² and 30 b³, and shaft b⁴, and owing to the shape of the blades said screw will rise or float, as it were, upon the solid material in the casing, carrying up with it the shaft b⁴. Such vertical motion moves upwardly the valve-rod 35 b⁵ and with it the valve C, thereby allowing the sugar or other material to escape through the conductors a³. If now this escape takes place at a more rapid rate than the inflow of material through the hopper-section a², the 40 upper level of the material in the casing will be lowered and the valve will be allowed to move downwardly far enough to close the opening in the lower portion of the section a¹. The hood c' being permanently and im- 45 movably fixed to the lower end of the tube c serves to prevent the material to be cooled from interfering with the operation of the valve C, while the hood d performs a similar service for the upper end of the valve-rod. 50 The trough-section around the lower edge of the cylindrical part of the casing A serves to catch any moisture which is condensed upon the outer surface of said casing and which would otherwise fall into the conical section 55 a' and possibly injure the material passing therethrough.

While I have described my device as applied to machinery primarily designed for the handling of sugar, it will be comprehended 60 by those skilled in the art that it may without material change be applied to any system for the handling of solid pieces or bodies of greater or less size to control delivery of the same to or from a vessel or other container, it being immaterial whether it is the supply or the delivery which is controlled.

It is evident that the vital features of my

device are in no way modified by the particular method of control adapted for material in traveling from one place to another, since, if desired, my improved flow-controlling device may be so designed as to permit the discharge of material more rapidly than it is supplied, or vice versa, or it may be made so that the discharge will be equal to the supply. 70

It will be noted that the application of the invention is exceedingly wide, since it may be employed to material undergoing chemical treatment, so that it is exposed for a definite time to the action of certain gas or liquids, or, as in the case illustrated, is applicable to physical processes where granular material is treated so as to change its temperature, or it may be applied to a process for storing or mixing solid materials where they 80 will be required to be agitated for a definite time. 85

While I have shown my device as applied to the regulation of the flow of solid materials held within containing vessels of relatively 90 small sizes, it is to be understood that the confinement of the material within such vessel is not essential to the operation of the device, since it is evident that the revolving screw operates the valve-controlling mechanism by virtue of changes in the level of the material operated upon, so that said material may be simply in the form of a pile upon the floor of a relatively large containing vessel, such as a room. 95

I claim as my invention—

1. The combination of a container having an outlet, a valve for said outlet, a device designed to remain upon the top of a body of material carried by the container and rigidly connected to said valve, with means for rotating said device, substantially as described. 105

2. The combination of a support for a body of solid material having an outlet for said material, a valve to said outlet, and a shaft directly connected to said valve having upon it a blade, with means for revolving said shaft, substantially as described. 110

3. The combination of a containing vessel having an outlet, a valve for closing said outlet, a shaft directly connected to said valve provided with means whereby it is revolved and a blade upon the shaft, the elements of said blade being radial and inclined to the shaft, substantially as described. 115

4. The combination of a containing vessel, a valved outlet thereto, tube-sheets within the vessel, tubes connecting said tube-sheets, a shaft provided with means whereby it is turned and extending through one of said tubes to the valve, with a screw upon the shaft designed to remain on the top of the body of material in the casing, substantially as described. 120

5. The combination of a containing vessel 125 provided with an outlet and tubes connecting the same, one of said tubes extending beyond one of the tube-sheets, a revoluble shaft having means whereby it is turned and

extending through said elongated tube, a valve fixed to said shaft, a hood fixed to said tubes and extending over said valve and means whereby said valve is made to close 5 whenever the material within the containing vessel falls below a predetermined level, substantially as described.

6. The combination of a containing vessel having tube-sheets and an opening for the admission of material to be treated, tubes connecting the tube-sheets, a conical section hung from the lower portion of said casing and provided with a valved outlet, a shaft extending from the vessel, a blade designed 15 to remain upon the upper surface of a body of material in the vessel and fixed to said shaft, said shaft having means whereby it is turned and being connected to the valve, substantially as described.

20 7. The combination of a containing vessel having tube-sheets and tubes connecting the same, one of said tubes extending above and below said tube-sheets, a shaft extending through said tube provided with means where- 25 by it is revolved, said containing vessel hav-

ing an outlet, a valve connected to the shaft and normally closing said outlet, said shaft having a screw fixed to it, a hood extending over the upper end of the elongated tube, and a second hood fixed to the lower end of 30 said tube and extending around the valve, substantially as described.

8. The combination of a containing-casing of substantially cylindrical form and open at the bottom, a trough around the outside of 35 the lower edge of the casing, a receiving-section hung below said casing, said section having an outlet and a valve therefor, with mechanism connected to said valve whereby the quantity of a solid within the casing may 40 be automatically regulated, substantially as described.

In testimony whereof I have signed my name to this specification in the presence of two subscribing witnesses.

GODFREY ENGEL.
